UNITED STATES PATENT OFFICE.

MANSFIELD C. CRAWLEY, OF GROTON, NEW YORK, ASSIGNOR TO ADDOGRAPH COMPANY, OF LOS ANGELES, CALIFORNIA, A CORPORATION OF CALIFORNIA.

TYPEWRITING MACHINE.

Application filed June 11, 1919, Serial No. 303,422. Renewed July 31, 1922. Serial No. 578,848.

To all whom it may concern:

Be it known that I, MANSFIELD C. CRAWLEY, a citizen of the United States, and resident of Groton, county of Tompkins, 5 and State of New York, have invented certain new and useful Improvements in Type-writing Machines, of which the following is a specification.

This invention relates to improvements in 10 case-shift mechanism for typewriting machines, and more particularly to means for shifting the platen vertically to provide for printing different-case characters.

In Patent No. 1,156,061, dated October 12, 15 1915, a power-operated typewriting machine is shown in which the type bars are moved to the printing point by means of an intermittently operating motor controlled by a constantly running motor. The platen 20 shift mechanism described herein is particularly adapted for use in machines of the type shown in said patent and application, but it will be obvious that it may be applied to other forms of machines provided with a 25 suitable motor.

In my Patent No. 1,455,109, dated May 15, 1923, and in my copending applications, Serial No. 188,771, filed August 29, 1917, renewed April 16, 1923, allowed January 5, 30 1924, and Serial No. 316,649, filed August 11, 1919, renewed January 23, 1924, power-operated case-shift mechanisms are shown possessing certain features in common with the mechanism shown and described in the present application which is subordinate to said Patent No. 1,455,109 and said applications, Serial No. 188,771 and Serial No. 316,649, the claims in the present case being confined to subject matter not disclosed in said patent 35 and applications. The objects of the present invention are to provide an efficient power-operated key-controlled case-shift mechanism and independent latches controlled by the keys and arranged on the 40 main frame to lock the shift mechanism in upper and lower case positions, respectively; to provide a power-shift mechanism adapted to be put into action by either of two keys and wherein latches are provided for locking 45 the shift frame in both upper and lower case position, one of said latches only being releasable by one of the keys while the other key is arranged to release both latches; to 50 provide means for connecting a source of power with a shift frame and independent 55

actuating devices for operating said connecting means, each of said devices being operable by a separate key lever and one of said devices being effective to release a lower case lock for the shift frame while the other device is effective to release both the lower case lock and an upper case lock; and to provide novel means for connecting a motor with a shift frame.

In the drawings, Fig. 1 is a vertical longitudinal sectional view of a typewriting machine provided with the improved case-shift mechanism;

Fig. 2 a fragmentary view similar to Fig. 1, but on an enlarged scale, the section being taken approximately on the line II—II of Fig. 4;

Fig. 3 a fragmentary vertical transverse section on the line III—III of Fig. 1;

Fig. 4 a fragmentary horizontal section on the line IV—IV of Fig. 2;

Fig. 5 a detail perspective view of a part of the mechanism for connecting the platen moving means with the power shaft; and

Figs. 6 and 7 detail views illustrating the operation of the two bails and the devices controlled thereby.

Referring to the various parts by numerals, 1 designates the side members, 2 the rear wall, and 3 the front plate of the frame 85 of the machine. A frame bar 4 extends transversely of the machine, said bar being held at its ends to the side members 1. A power shaft 5 is journaled in suitable bearings in brackets 69 in the frame, and said shaft is continuously rotated when the machine is in use by a pulley 6 driven by a belt 7 and a pulley 8 on the drive shaft of an electric motor 9. The motor 9 is held to the rear wall 2 of the frame by a suitable bracket. A worm 10 is fixed on the shaft 5 to rotate therewith, and the mechanism for shifting the platen to upper-case position is adapted to be connected with and operated by said worm as hereinafter described.

The platen carriage 11 is supported to travel transversely of the frame, the frame being provided with raceway members 14 and 15 and the carriage being provided with cooperating raceway members 12 and 13. 105 Suitable ball bearings are confined in the raceways formed by said members. The forward end of the carriage is supported by a roller 16 held to the front cross bar 17 of the carriage midway the length of the car- 110

riage, said roller traveling along a track 18 held to the frame. The platen 19 is rotatably supported by a platen shaft 20 the ends of which extend through slots 21 in the side members of the carriage frame. The platen shaft 20 extends through and is journaled in the forward ends of a pair of rock arms 22 held to a rock shaft 23 which is journaled at its ends in the side members of the carriage 5 members of the carriage frame. The platen shaft 20 extends through and is journaled in the side members 24 of a U-shaped shift frame. The members 24 of the shift frame are connected at their forward ends by a crossbar 25, and the rock arms 22 are rigidly connected by a rod 26. The rock arms are provided with extensions 22^a normally resting on a pair of adjustable stop screws 27 tapped through lugs 28 extending inwardly from the side members of 10 the carriage to support the platen in its normal lower-case position. The extensions 22^a on the rock arms 22 are adapted to engage a pair of adjustable stop screws 29 tapped through lugs 30 extending inwardly 15 from the side members of the carriage 11 to limit the upward movement of the shift frame and arrest the platen at its upper-case position. The carriage is provided with a rack 31 meshing with a pinion 32 on a 20 shaft 33. A bevel gear 34 on shaft 33 meshes with bevel gears 35 and 36 loosely mounted on shaft 5, the carriage being shiftable transversely of the frame, for letter spacing and for returning the same, by suitable 25 mechanism such as that described in my co-pending applications Serial Nos. 188,770 and 188,772 filed August 29, 1917. The axis of the rock shaft 23 is so positioned relatively to the axis of the platen shaft 20 30 that the platen shaft will move from a point below the plane of the rock shaft to a point an equal distance above the plane of the rock shaft when the platen is moved to upper-case position. Means is provided for insuring such a case shift movement of the platen 35 that the printing point will move between two positions in direct vertical alignment, said means embodying a pair of pins 37 projecting outwardly from the side members 24 of the shift frame and engaging in vertical guideways formed by two pairs of vertical ribs 38 on the inner sides of the side members of the platen carriage 11. As the platen shaft 20 swings through an arc from 40 a point below the plane of the axis of rock shaft 23 to a point an equal distance above said plane, it will be obvious that the platen shaft and pins 37 will be in vertical alignment in both the upper and lower case positions of the platen.

The rod 26, held to rock arms 22, rests upon a roller 39 journaled on the shank of a screw 40 held to the upper portion 41 of a vertically reciprocable two-part bar. The 45 portion 41 of the bar is provided with a forwardly bent hook-like upper end 42 engaging over rod 26 and serving to prevent vertical movement of the rod relatively to roller 39, while permitting a slight forward and rearward movement of said rod 70 relatively to the roller during the up and down movement of the rock arms 22. The upper portion 41 of the reciprocable shift frame lifting bar is formed with a short slot 43 in which a lug 44 on the upper end of the lower portion 45 of said bar engages, and the lower portion of the bar is formed with a short slot 46 in which a lug 47 on the lower end of the upper portion 41 of the bar engages. A spring 48 coiled about the overlapping ends of the two parts of the bar serves to normally maintain said parts in extended relation, but permits a slight telescoping movement of the parts of the bar upon engagement of the extensions 22^a on rock arms 22 with the stops 29, the extent of movement of the bar being preferably slightly greater than the extent of movement of the platen, to insure movement of the printing point to proper upper-case position. The telescoping of the parts of the bar serves also to prevent jamming or injury to the parts of the shift mechanism, which might otherwise result from inaccuracies in adjustment or size of various parts 90 upon engagement of extensions 22^a with stops 29. The parts 41 and 45 of the shift frame lifting bar are formed with pairs of lugs 41^a and 45^a, respectively, forming abutments against which the ends of the spring 95 48 engage.

The shift frame lifting bar is slidably held to two brackets 49 and 50 by screws 51 and 52 extending through vertical slots 53 and 54 in the bar and threaded into said brackets. The brackets 49 and 50 are formed on a vertical frame member 55 and said member is also formed with a bracket 56 extending forwardly and downwardly in front of the transverse frame bar 4. A lever 57 is pivotally held to bracket 56 by a pivot screw 58, said lever being connected adjacent its forward end by a pivot screw 59 with the lower end of the vertically reciprocable shift frame lifting bar, and being pivotally connected 100 at its rear end by a pivot pin 60 with the lower end of a link 61. The link 61 is pivotally connected at its upper end by a pivot pin 62 with one arm 63 of a bell-crank lever. The bell-crank lever is pivotally held to the forward end of a bracket 64 by a pivot screw 65, and one end of a worm-engaging dog 66 is pivotally held to the other arm 67 of the bell-crank lever by a screw 68. The free end of the dog 66 is 105 normally supported in a notch 70 in a guide plate 71. The guide plate 71 is held to a bracket 72 fixed to a part of the machine frame.

The dog 66 is provided with a lateral pro-

jection or lug 73 adapted to be engaged by a shoulder 74 formed adjacent the upper end of the upper portion 75^a of a two-part vertically reciprocable dog-lifting bar 75. The lower part of bar 75 is slidably held against the outer face of a boss 76, formed on the rear side of the transverse frame bar 4, by two screws 77 passing through slots 78 in the bar. The lower end of the dog-lifting bar 75 is bent forwardly to form a foot, projection or abutment 79, and said bar is adapted to be forced upwardly to engage the hook end 66^a of dog 66 with worm 10 through the instrumentality of either of three shift-key levers 80, 81 and 82 fulcrumed on a pivot rod 83 held at its ends to the side members 1 of the machine frame. The shift-key levers 80 and 81 are arranged at the left-hand side of the machine and the shift-key lever 82 is arranged at the right-hand side of the machine. The lever 82 performs the same function as lever 80 and may be omitted if desired. The key levers 80, 81 and 82 are yieldably held in their normal positions by suitable springs 86.

The shift-key levers 80 and 82 are provided with inwardly extending lugs or projections 80^a and 82^a, respectively, engaging under the side members of a U-shaped bail or rocking member 84 pivotally held by pivot screws 86' to brackets 85 secured to the side members 1 of the machine frame. It is obvious that when either the shift key on key lever 80 or key lever 82 is depressed the bail 84 will be lifted, and that when pressure of the finger upon the shift key carried by the lever is relieved the bail will swing downwardly by gravity to its normal position. A rearwardly extending lug or projection 87 is stamped from the lower edge of the transverse member of bail 84 and engages under the foot or forwardly bent lower end 79 of the dog-lifting bar 75. A U-shaped bail or rocking member 88 is pivotally held by screws 89 to a pair of brackets 90 fixed to the rear side of frame bar 4. The bail 88 has a forwardly extending lug or projection 91 stamped therefrom adjacent one end, under which the inwardly bent lug 81^a on shift-key lever 81 engages, and said bail extends below the foot 79 on dog-lifting bar 75, the upper edge of the bail having a portion thereof cut away at 88^a to receive the foot 79. It will be obvious that when the key carried by shift lever 81 is depressed the bail 88 will be lifted, and that when pressure on the key is relieved the bail will return by gravity to its normal position. It will also be noted that the bails 84 and 88 are operable independently of each other.

A pair of locking devices or latch levers 92 and 93 are pivotally held intermediate their ends to a forwardly extending arm 56^a on bracket 56, by a pivot screw 94. The latch lever 92 is formed with a hook or rearwardly extending portion 92^a at its upper end, the straight lower edge of which engages over a laterally bent extension, arm or lug 57^a formed on the forward end of lever 57 to lock the shift frame and platen in normal lower-case position. The latch lever 93 is formed with a rearwardly extending projection or lug 93^a having a straight upper edge adapted to engage under the lug 57^a to lock the platen and shift frame in upper-case position, the upper edge of lug 93^a being higher than the straight lower edge of lug 92^a, and the lower edge of lug 93^a being beveled or inclined upwardly and rearwardly as shown to permit lug 57^a to ride upwardly over said lug 93^a. The latch levers 92 and 93 are operated by releasing or controlling levers 95 and 96, respectively, held by a pivot screw 97 to the lower end of bracket 56. The lower edges of both of the releasing or controlling levers 95 and 96 rest upon the upper edge of the transverse member of bail 84, but it will be seen that lever 96 terminates forwardly of the bail 88. Releasing lever 95 is formed with a downwardly extending arm 95^a at its rear end, engaging over a forwardly extending lug or projection 98 stamped from the lower edge of bail 88, and the upper edge of bail 88 is slotted at 88^b to permit relative movement between the bail and arm 95^a when the parts are shifted upwardly as shown in Figs. 6 and 7. The latch lever 92 and its releasing lever 95 are connected by a coiled spring 99, and latch lever 93 and its releasing or controlling lever 96 are connected by a similar coiled spring 100, said springs serving to yieldably hold the levers in their normal positions. The locking lever 92 is formed with a forwardly and downwardly inclined cam surface 92^b adjacent its lower end upon which the laterally bent forward end 95^b of releasing lever 95 is adapted to ride. The locking lever 93 is formed adjacent its lower end with two oppositely inclined cam surfaces 93^b and 93^c upon which the laterally bent forward end 96^a of releasing lever 96 is adapted to ride, the cam surface 93^b being parallel with cam surface 92^b on lever 92 but terminating above the lower end of said cam surface 92^b.

When it is desired to shift the platen to upper-case position for a comparatively brief period of time to print one or a small number of upper-case characters, the operator depresses either the shift key 80^b carried by key lever 80 or the shift key 82^b carried by the key lever 82. As the key levers 80 and 82 perform the same functions, further description of the operation of the parts through the medium of lever 82 is unnecessary. When key 80^b is depressed the rear end of shift lever 80 is elevated, causing the inwardly bent end 80^a thereof to rock 130

bail 84 upwardly and thus forcing the dog-lifting bar 75 upwardly and also rocking both latch-releasing levers 95 and 96. The hook end 92^a of latch 92 is thus rocked out 5 of engagement with lug 57^a on lever 57 as the lug 95^b on releasing lever 95 moves downwardly over cam surface 92^b on latch 92. The projection 93^a on latch 93 is also rocked out of the path of lug 57^a as lug 96^a on lever 10 96 moves downwardly over cam surface 93^b on latch 93. The upward movement of bar 75 elevates the free end of dog 66, and causes the hooked end 66^a of the dog to engage in the threads of worm 10 on the constantly 15 driven shaft 5. When dog 66 is raised the lug 101 thereon moves upwardly through a notch 102 in a horizontal flange 103 on guide plate 71 and passes over the upper face of said flange 103 as the dog is pulled toward 20 the right side of the machine, thus holding the hook 66^a in engagement with the worm until lug 101 drops off the right-hand edge of flange 103. The movement of the dog toward the right-hand side of the machine 25 rocks the bell-crank lever, forcing link 61 downwardly and elevating the forward end of lever 57, and thus forces the shift frame lifting bar upwardly and moves the platen to upper-case position. As the forward end 30 of lever 57 moves upwardly, the lug 96^a on releasing lever 96 leaves the cam surface 93^b on latch 93 and engages the oppositely inclined cam surface 93^c on the latch, thus permitting the upper end of the latch to 35 move rearwardly to its normal position, whereupon the projection 93^a on the latch will snap under lug 57^a on lever 57 and positively lock the shift frame lifting bar and the platen and shift frame in upper-case 40 position with stops 22^a on arms 22 engaging stop screws 29 on the platen carriage. The upper and lower sections of bar 75 are pivotally held together by a pin 104, and the upper section 75^a of said bar is normally held 45 by a spring 106 against a lug 105 formed on one edge of the lower section of the bar, said spring 106 being connected to arm 63 of the bell-crank lever and serving to yieldably hold the section 75^a of the bar and the bell- 50 crank lever in their normal positions. Said spring also tends to force bar 75 downwardly to its normal position. The spring 106 permits the pivoted upper section 75^a of bar 75 to yield slightly toward the left when lug 55 73 on dog 66 is pulled against said section 75^a by the spring 107 after the dog is disengaged from the worm, the shoulder 74 being above the path of lug 63 at this time.

The operator holds the key 80^b on shift 60 lever 80 in depressed position until the desired upper-case character or characters have been printed, whereupon the platen may be restored to normal-case position by simply releasing key 80^b and permitting the rear end of lever 80 and bail 84 to move down-

wardly to their normal positions. As bail 84 moves downwardly lug 96^a on releasing lever 96 rides upwardly along cam surface 93^c on latch 93 and then over cam surface 93^b, thus first moving projection 93^a on latch 70 93 out from under lug 57^a on lever 57, permitting the platen and shift frame to move downwardly to lower-case position and latch 93 to subsequently move to its normal position. During the restoration of bail 84 and 75 the platen and shift frame to lower-case position the lug 95^b on releasing lever 95 rides upwardly along cam surface 92^b on latch 92, permitting hook 92^a on the latch to engage over lug 57^a on lever 57 as the parts 80 reach normal-case position, thus positively locking the platen against upward movement.

It will be observed that, while it is necessary for the operator to hold the shift key 85 on lever 80, or on lever 82, depressed while writing the upper-case characters, the operator is relieved not only of the effort of lifting the platen, shift frame, etc., but is also relieved of the effort of holding said 90 parts in upper-case position, power mechanism being provided for lifting the parts and an automatic latch serving to positively hold and support the parts in upper-case 95 position until the key is released.

When it is desired to hold the platen in upper-case position for a relatively long period of time while writing a large number of upper-case characters, the operator depresses and immediately releases the key 81^b 100 carried by shift lever 81. The depression of key 81^b elevates the rear end of lever 81 and moves bail 88 upwardly. The upward movement of bail 88 lifts bar 75 and also rocks releasing lever 95, but does not move 105 releasing lever 96. The rocking of lever 95 releases hook 92^a on latch 92 from lug 57^a on lever 57 and the upward movement of bar 75 engages dog 66 with worm 10, whereupon the platen is moved to upper-case 110 position in the manner heretofore described. As the forward end of lever 57 moves upwardly, lug 57^a thereon will wipe over the inclined lower edge of projection 93^a on latch 93 and said projection will 115 snap under lug 57^a and lock the parts in upper-case position. It will be seen, however, that the release of key 81^b, while it permits bail 88 and releasing lever 95 to return, will not affect releasing lever 93, and that the platen, therefore, will remain locked 120 in upper-case position. The straight rear face of hook 92^a on latch 92 preferably extends sufficiently high above projection 93^a on latch 93 to prevent hook 92^a engaging under lug 57^a when key 81^b is released. From the foregoing it will be seen that the platen may be shifted to upper-case position by power mechanism, and locked in that 125 position by simply depressing and releasing a 130

single key. When it is desired to restore the platen to lower-case position after an operation of key 81^b, it is simply necessary to depress either of the other two shift keys 80^b or 82^b, whereupon bail 84 will move up, first rocking latch 93 out from under lug 57^a, permitting the platen to move downwardly, and then when the key-lever is released permitting the latches 92 and 93 and releasing levers 95 and 96 to return to their normal 10 positions with hook 92^a on latch 92 engaged over lug 57^a. The actuation of bail 84 will also cause an idle operation of bar 75.

Any suitable means may be employed for 15 moving the type bars 108 mounted in the segment 109 upwardly and rearwardly to the printing point through the instrumentality of printing key levers 110 such, for example, as that shown and described in the 20 patent and application hereinbefore referred to.

What I claim is:

1. Case shift mechanism for a typewriting machine comprising a main frame, 25 a shift frame, means for shifting said frame, a source of power for actuating said shifting means, means for operatively connecting said shifting means with the source of power, means on the main frame for locking said shift frame in lower case position, independent means on the main frame for locking said shift frame in upper case position, and means operable by a single key for releasing the lower case locking means 30 and actuating said connecting means when the key is depressed and for releasing the upper case locking means when the key is released.

2. Case shift mechanism for a typewriting 40 machine, comprising a shift frame, means for shifting said frame, a source of power for actuating said shifting means, means for operatively connecting said shifting means with the source of power, 45 means for locking said shift frame in lower case position, independent means for locking said shift frame in upper case position, two shift control keys, means controlled by one of said keys for releasing the lower case 50 locking means and actuating said connecting means when the key is depressed and for releasing the upper case locking means when the key is released, and independent means controlled by the second key for releasing 55 only the lower case locking means and actuating said connecting means when the second key is depressed and released.

3. Case shift mechanism for a typewriting 60 machine, comprising a shift frame, means for shifting said frame, a source of power for actuating said shifting means, means for operatively connecting said shifting means with the source of power, two shift control keys, means for locking said 65 shift frame in lower case position, independent

means for locking said shift frame in upper case position, means operable by one control key for releasing the lower case locking means and actuating said connecting means when the key is depressed and 70 for releasing the upper case locking means when the key is released, and independent means operable by the second control key for releasing the lower case locking means and actuating said connecting means when 75 the second key is depressed and released, said first mentioned key operated means being operable to release the upper case locking means after an actuation of the second key-operated means. 80

4. Case shift mechanism for a typewriting machine, comprising a shift frame, means for shifting said frame, a source of power for actuating said shifting means, means for operatively connecting said shifting means 85 with the source of power, two shift control keys, means for locking said shift frame in lower case position, independent means for locking said shift frame in upper case position, means controlled by one of said keys 90 for releasing the lower case locking means and actuating said connecting means when the key is depressed and for releasing the upper case locking means when the key is released, and independent means controlled 95 by the second key for releasing the lower case locking means and actuating said connecting means when the second key is depressed and released, said first mentioned key controlled means being operable to release the upper case locking means after an actuation of the second key-controlled means without connecting the source of power with the frame shifting means. 100

5. Case shift mechanism for a typewriting 105 machine comprising a shift frame, means for automatically locking the frame in lower case position, means for shifting the frame embodying a continuously-running motor, independent means for automatically locking 110 the frame in upper case position, a shift control key, and means movable under control of said key for releasing the lower case locking means and putting the motor in action for shifting the frame to upper case position when the key is moved in one direction and for releasing the upper case locking means during the return movement of the key. 115

6. In a power-operated key-controlled 120 case shift mechanism, the combination of a worm, power means for rotating the worm, a pivotally supported shift-frame-moving element, a dog pivotally held to said element and extending longitudinally of the worm and movable endwise by the worm, a manually-reciprocable bar having a slidably held portion and a dog-engaging portion pivoted to said slidably held portion, means for yieldingly holding the pivoted portion 125 130

- of the bar in position to force the dog into the worm, said dog having a laterally extending lug and said pivoted portion of the bar being cut away at its free end to form 5 an abutment normally engaging under one face of the lug and an abutment between the lug and the pivoted end of the dog, a spring connecting the dog with said pivotally supported element tending to normally with- 10 draw the dog from the worm, and means for holding the dog in engagement with the worm for a predetermined travel of the dog after movement of the dog by the bar into engagement with the worm.
- 15 7. In a case-shift mechanism, the combination of a power-driven worm, a shift frame moving mechanism including a dog, a manually reciprocal bar having a slidably mounted section and a yieldable dog-engag- 20 ing section, said bar being movable endwise to shift the dog into engagement with the worm, means for holding the dog in engagement with the worm after an engagement thereof effected by said bar until a predeter- 25 mined extent of movement of the dog takes place irrespective of return movement of the bar, and means for retracting the dog.
8. In a typewriting machine, the combina- 30 tion of a shift frame, means for shifting said frame, a source of power for operating said shifting means, means for connecting the frame shifting means with the source of power, independent actuating devices for operating said connecting means, a shift key 35 lever for operating one of said actuating devices, a second shift key lever for operating the other actuating device, independent locking devices for automatically locking the shift frame in lower and upper case posi- 40 tions, and independent devices for releasing said locking devices, both of said releasing devices being operatively connected with one of the actuating devices and the lower case locking device being also operatively connected with the other actuating device.
- 45 9. In a typewriting machine, the combina- 50 tion of a shift frame, power operated means for shifting said frame, a pair of independent locking devices for automatically lock- 55 ing the frame in its different case positions, key operated means for controlling the power operated means operatively connected to actuate both of said locking devices, and independent key operated means for control- 60 ling the power operated means operatively connected to actuate one of said locking devices only.
10. In a typewriting machine, the combi- 65 nation of a shift frame, power-operated lever mechanism for shifting said frame, a pair of independent locking devices for automatically locking the frame in its normal and shifted positions, key-operated means controlling the frame shifting means opera-

tively connected to actuate both of the locking devices, and independent key operated means for controlling the frame shifting means operatively connected to actuate only the locking device holding the frame in normal position.

11. In a typewriting machine, the combination of a shift frame, a source of power, lever mechanism for elevating the shift frame operable by the source of power and normally disconnected therefrom, a shiftable device for connecting the lever mechanism with the source of power, a pair of independent latches for automatically locking the shift frame in its upper and lower case positions, a pair of shift key levers, means operable by one of said levers for shifting said connecting device and operating both of said latches during a single operation of the lever, and means operable by the other key lever for shifting said connecting device and actuating the lower case latch solely during a single operation of the lever.

12. In a typewriting machine, the combination of a shift frame, independent locking devices for automatically locking the frame in its lower and upper case positions, a key lever operatively connected to release both of said locking devices, a second key lever operatively connected to release only the lower case locking device, and power operated means for moving the frame to upper case position adapted to be put into action by either of said key levers independently of the other.

13. In a typewriting machine, the combination of a shift frame, independent locking devices for automatically locking the frame in its lower and upper case positions, a key lever operatively connected to release both of said locking devices, a second key lever operatively connected to release only the lower case locking device, a source of power, means operable by the source of power for moving the frame to upper case position, and a shiftable device for connecting the frame moving means with the source of power operable by either of said key levers independently of the other.

14. In a typewriting machine, the combination of a main frame, a shift frame, a shifting mechanism for the frame, a continuously operating power means, a control key, means operated by depression of said key for connecting the shifting mechanism with said power means to effect movement of the shift frame to upper case position, means for automatically effecting disconnection of the shifting mechanism from the power means when the shift frame is shifted into upper case position independently of release of the key, automatic locking means on the main frame for holding the shift frame in lower case position, and automatic

locking means on the main frame for holding the shift frame in upper case position, said first-mentioned locking means being releasable by said key-operated means upon depression of the key and said last-mentioned locking means being releasable by said key-operated means upon release of the key.

15. In a typewriting machine, the combination of a shift-frame, a shifting mechanism therefor, and a continuously-running motor means adapted to actuate said mechanism when connected thereto, key-controlled means for connecting the motor means to the shifting mechanism to thus shift the shift-frame, said shifting mechanism embodying means whereby the motor means is automatically disconnected therefrom after the shifting movement has been completed, a latch independent of the shifting mechanism for holding the shifting mechanism in its shifted position, and another key-controlled mechanism for releasing the latch to thus permit the shift-frame and the shifting mechanism to return to 25 normal.

16. In a typewriting machine, the combination of a main frame, a shift frame, an upper-case latch and a lower-case latch pivotally mounted on the main frame normally urged to locking position and arranged to hold the shift frame in upper-case and lower-case positions respectively, a control key, means operated by said key when the key is depressed adapted to move the lower-case 30 latch to release position and permit a locking movement of the upper-case latch, said key-operated means being adapted when the key is released to move the upper-case latch to release position and permit a locking movement of the lower-case latch, and motor-operated means controlled by said key-operated means for moving the shift frame.
